(Cl. D58—12)

To all whom it may concern:

Be it known that we, Arline A. Elisayeff and Edward F. Loeschorn, respectively, a citizen of the United States residing in New York city, in the county of New York and State of New York, and a citizen of the United States residing in Bogota, in the county of Bergen and State of New Jersey, have invented a new, original, and ornamental Design for a Box Cover or the like, of which the following is a specification, reference being had to the accompanying drawing, forming part thereof.

The figure is a plan view of a box cover or the like showing our new design.

The nature of the design is substantially thin and flat.

We claim:

The ornamental design for a box cover or the like, substantially as shown, and described.

ARLINE A. ELISAYEFF.
EDWARD F. LOESCHORN.
